[57] **ABSTRACT**

A photoelectrophoretic ink is spread over a flat transparent plate by a first roller traveling over the plate along a first path. Voltages are coupled to the first roller and plate and radiation is directed onto the ink for forming an image as the roller travels over the plate. A second roller travels over the plate along a path that intersects the first. The first and a third roller are used for image forming, and the second roller is used for image transferring. Web handling mechanisms are provided to feed webs between the rollers and plate as a roller moves over the plate.

PHOTOELECTROPHORETIC APPARATUS

BACKGROUND OF THE INVENTION

This invention relates to imaging systems and in particular to novel method and apparatus for the photoelectrophoretic imaging process. Even more specifically, this invention relates to photoelectrophoretic machines.

In the photoelectrophoretic imaging process, an image is formed from an imaging suspension or ink by subjecting the ink to an electric field and exposing it to activating electromagnetic radiation, e.g., light in the visible spectrum. The imaging suspension is composed of light sensitive particles suspended within an insulating liquid carrier. The particles are believed to bear a net electrical charge while in suspension. Conventionally, the ink is placed between injecting and blocking electrodes used to establish the electric field and is exposed to a light image through one of the electrodes which is at least partially transparent. According to one theory, particles attracted to the injecting electrode by the electric field exchange charge with the injecting electrode when exposed to light and migrate under the influence of the field through the liquid carrier to the blocking electrode. As a result of the migration, positive and negative images are formed on the two electrodes. The blocking electrode is covered with a dielectric material to minimize charge exchange and thereby prevent the particles from oscillating back and forth between the two electrodes.

The photoelectrophoretic imaging process is either monochromatic or polychromatic depending upon whether the light sensitive particles within the liquid carrier are responsive to the same or different portions of the light spectrum. A full color polychromatic system is obtained, for example, by using cyan, magenta and yellow colored particles which are responsive to red, green and blue light respectively. An extensive and detailed description of the photoelectrophoretic process is found in U. S. Pat. Nos. 3,384,565 and 3,384,484 to Tulagin and Carreira, 3,383,993 to Yeh and 3,384,566 to Clark.

Conventionally, photoelectrophoretic imaging apparatus have included multiple roller electrodes that travel one after the other across a flat plate electrode or alternately the plate is moved in a straight path over first, second, third and even more rollers. The first roller may be for electrophoretically applying an ink to the plate, the second for applying electric field during first exposure, the third to apply an electric field during a second exposure and the fourth for transferring an image formed over the plate electrode. Additional rollers may be for cleaning the surface of the plate after transfer. The multiple rollers provide excellent images and system operation but their presence tends to enlarge the overall dimensions of a machine. In addition, if consumable webs are used with each roller the apparatus is greatly complicated by complex web handling mechanisms.

Accordingly it is an object of this invention to simplify apparatus for the photoelectrophoretic imaging process.

Another object is to reduce the overall length of multiple roller photoelectrophoretic imaging machines.

Yet a further object of the present invention is to build novel web handling means for the photoelectrophoretic process.

Still another object of the invention is to enhance the photoelectrophoretic process itself by performing electric field averaging over the exposed photoelectrophoretic ink.

These and other objects are accomplished by a novel multiple roller photoelectrophoretic imaging machine wherein some rollers travel over a plate along a path at an angle to the path followed by other rollers. Alternately, a plate is moved in a first direction over one set of rollers and in a second direction over another set of rollers. For clarity of presentation, only the prior case is discussed in detail. The simplest embodiment is wherein the first set of roller(s) travel at right angles to the path followed by a second set of roller(s). All the rollers have a disposable web wrapped around them between the roller and plate. The mechanism for handling the webs are carried immediately above the rollers and are independent of one another.

Photoelectrophoretic ink is introduced into the machine by means of a disposable film sheet having an image forming area and a rupturable pod for housing the ink. The film sheet is stretched out over the plate and the first roller passing over it ruptures the pod to release the ink. The ink is then spread over the film sheet by the continuing motion of the roller.

DESCRIPTION OF THE DRAWINGS

FIG. 1 is a perspective view of the film sheet employed in the present apparatus.

FIG. 2 is a perspective view of a pyramid rack gear used at an intersection between rack gears to permit one set of rollers to travel across the path traveled by other rollers.

FIG. 3 is a partial side elevation view of the present photoelectrophoretic machine.

FIG. 4 is a plan elevation view of the present machine with the web handling mechanisms removed.

FIG. 5 is a side sectional view of first web handling mechanisms for a set of two rollers used in the present machine.

FIG. 6 is a side sectional view of a second web handling mechanism used in the present machine.

DESCRIPTION OF THE EMBODIMENTS

FIG. 4 illustrates most of the components of the present machine 1. Machine 1 includes the frame 2, the transparent flat plate 3, first and second imaging rollers 4 and 5 and transfer roller 6. The imaging rollers are supported for travel over plate 3 by means including the imaging rack gears 8 and 9. The transfer rollers are supported for travel over substantially the same area of plate 3 by means including the transfer rack gears 10 and 11. In the specific embodiment shown in the drawings the path followed by the rollers 4 and 5 intersects the path followed by roller 6 at an angle of about 90°. This angle of intersection may be varied to suit the needs of different apparatus. The 90° angle is particularly advantageous because it allows the length of the machine to be shortened significantly; namely, by an amount proportional to the size of a roller. Furthermore, the process is enhanced because the electric fields applied between the rollers and plate are averaged.

Images or copies are formed with machine 1 by spreading a photoelectrophoretic ink over an image forming area of film sheet 13 (FIG. 1) that rests on

plate 3. Conventionally, plate 3 is electrically grounded and the three rollers 4, 5 and 6 have high voltages coupled to them. An image is projected to the ink on a film sheet by the exposure means 14 (FIG. 3). The electric field established between the first imaging roller and plate and the activating electromagnetic radiation, e.g., light in and near the visible spectrum, cause migration of ink particles that result in the formation of a negative image on roller 4 (or a web wrapped around it) and a positive image on the film sheet.

Alternately, the electric field applied between roller 4 and the plate 3 may be used to electrophoretically deposit the particles in the ink onto the film sheet while no radiation is being projected. The electric field between roller 5 and plate 3 is used along with the exposure to create the images. If the images are formed with the first roller as described, the second roller 5 is used to subject the ink image on the film sheet to a second exposure and electric field. This second exposure to light and application of field improves the quality of polychromatic images.

The transfer roller 6 has a voltage polarity that establishes an electric field between it and plate 3 opposite in direction to that used to form the image on the film sheet. This field attracts the ink pigments on the film sheet to the roller (or a web wrapped around it) thereby removing or transferring the ink image from the film sheet. The electric field and the mechanical movement of the roller 6 over the plate at the 90° intersection angle tends to offset or average out variations in the resultant transferred image due to variations in the electric field and the mechanical contact between roller and plate. The averaging can be used in forming the image also. In this case, the functions of the second imaging roller 5 and transfer roller 6 are interchanged. The first imaging roller 4 travels over the plate 3 with light on and voltages applied to form an ink image. Next the roller 6 passes over the plate at the 90° intersecting angle to expose the ink image and subject it to field a second time. Next the roller 5 is passed over the plate to transfer the ink image to it (or a web wrapped around it). A suitable mechanism is used to elevate roller 5 out of contact with a film sheet 13 on plate 3 when roller 4 is passed over the plate and to elevate roller 4 out of contact with a film sheet when roller 5 is passed over the plate.

The photoelectrophoretic ink used to form the ink images is introduced into the process by means of the film sheet 13. The film sheet includes a paper body 15, transparent image forming section 16 and the rupturable pod 17. The pod contains the ink and releases it when crushed by one of the rollers. The pod is a paper or plastic sack glued or otherwise appropriately attached to the body 15. The transparent section is glued or otherwise appropriately attached to body 14 over the cut-out 18 on the side opposite the pod. It is transparent to the radiation projected by the exposure means 14. The transparent section or sheet is on the side opposite the pod to provide a border for the image on the film sheet when it is not transferred. The transparent sheet 16 is separated from the body 6 to provide the final product. Because the ink is spread over the transparent sheet only in areas of cut-out 18 in body 14, the border is inherently provided for the ink image.

The film sheet is stretched out over the flat plate 3 (with pod 17 facing upward) by means of the hooks 20 and 21 on either side of plate 3. The film sheet has holes 22 and 23 on opposite ends that mate with the hooks. An appropriate spring bias mechanism is coupled to one set of hooks to tightly stretch the film sheet across the plate.

The rollers 4, 5 and 6 are composed of conductive metal cores having conductive rubber wrapped around their peripheries to give good compliance between the rollers and plate 3. The rollers include means for coupling to appropriate voltage sources. Rollers 4 and 5 are journeled for rotation in the side walls 25 and 26 of carriage 27 while transfer roller 6 is journeled for rotation in side walls 29 and 30 of carriage 31. The carriages are movably coupled to the rack gears 8-11 for travel along paths defined by the rack gears.

Carriage 27 is coupled to rack gears 8 and 9 by the pinion gears 33-36. The pinion gears are mated with the rack gears and are journeled in the side walls of the carriage to support the carriage. The electric motor 37 is mounted on the carriage and is drivingly coupled by appropriate means such as pulleys and belt to pinion gears 33 and 34 for rotating them and propelling the carriage along racks 8 and 9 over the plate 3. The motor is reversible to allow travel in two directions over the plate.

Carriage 31 is coupled to rack gears 10 and 11 by the pinion gears 40-43. The pinion gears are mated with the rack gears and are journeled for rotation in the side walls of the carriage 31 to support the carriage. The electric motor 45 is mounted on the carriage and is drivingly coupled by appropriate means such as pulleys and belt to pinion gears 40 and 41 for rotating them and propelling the carriage along racks 10 and 11 over the plate 3. The motor 45 is reversible to allow travel in two directions.

The rollers 4, 5 and 6 are mounted in their respective carriages at elevations relative to plate 3 to cause them to be forced by the weight of the carriage against the plate (or a web and film sheet between the rollers and plate). The bearing blocks in which the rollers are journeled may be coupled to lift or elevator mechanisms that raise or lower the elevation of the rollers relative to the plate. The elevators are used to hold a roller out of contact with the plate during the carriage's travel or to urge a roller under pressure against plate 3.

The webs 50 and 51 shown in FIG. 5 are wrapped around rollers 4 and 5 to serve as the blocking layer during first and second imaging (exposure to light and application of field) of ink on the film sheet. The webs include electrically insulating materials and they are wound between the supply reels 52 and 53 and the take-up reels 54 and 55, respectively. The supply reels have drag brakes coupled to them to maintain tension in the webs. The take-up reels are drivingly coupled by appropriate means to the motor 37. The web is pulled around the free rolling rollers 4 and 5 at a velocity substantially equal to the translational speed of the carriage but in the opposite direction. The webs are used to eliminate the need to clean the periphery of the rollers.

The transfer web 57 shown in FIG. 6 is wrapped around the transfer roller 6 and is the final support for the ink image formed on the film sheet. The web 57 is

wound onto the supply reel 58 and pulled therefrom by the friction drive mechanism including opposed rollers 59 and 60. Roller 59 is drivingly coupled to motor 45 to pull the web 57 around free rolling roller 6 at a velocity about equal and opposite to the translational velocity of the carriage.

The webs 50, 51 and 57 are wrapped around their respective rollers 4, 5 and 6. The reels supporting the webs are coupled to the side plates of the carriages 27 and 31 respectively. The reels are fixedly supported relative to the rollers to move with them. The reels are mounted on the same side of the rollers to obtain the wrap around and are mounted generally vertically above the rollers to take-up the least possible room. They are positioned on the opposite side of the rollers from plate 3 so that they are drawn tightly against the rollers and so that if any skid or slip between the webs and plate occurs the webs are unlikely to be pulled off the roller. The drive mechanism pulling the webs around the rollers do so at a velocity equal and opposite to that of the carriage to prevent skidding or slipping. The resultant web handling mechanisms are compact, efficient and independent of one another so that it is unlikely that one web will get in the way of another, i.e., adversely interfere with the feeding or threading of each other.

The exposure means 14 shown in FIG. 3 includes the lamp 61, transparency 62, and lens 63. This mechanism can be replaced by reflection exposure means for projecting an image of an opaque original. The plate 3 and the film sheet are transparent to the electromagnetic radiation generated by lamp 4 to allow the radiation to act on ink on the film sheet between a roller and plate. The frame 2 includes the cut-out 64 to permit the radiation image pattern to reach the plate 3.

The plate 3 includes transparent plate glass having a transparent conductive layer such as tin oxide on its side facing the rollers. The conductive layer is normally coupled to electrical ground.

The carriages 27 and 31 are able to intersect each other's path because of the pyramid gears placed at the intersections of the rack gears. The isolated, perspective view of intersection 65 (FIG. 2) is representative of the three other intersections. Sections of rack gears 8 and 11 are cut-out at the vicinity of the intersection of gears 8 and 11 and the removed pieces are replaced by the pyramid gear 66. Each rack gear includes a body 67 having the triangular cross-section, linear teeth 68. The teeth of each rack gear are identified by their height 69 and their peak-to-peak spacing 70, or pitch. The height and pitch of the different gears are designed to mate with like teeth on the pinion gears 33-36 and 40-43. The height and pitch are generally the same for all gears in this embodiment but may vary one from the other in different embodiments.

The pyramid gear is formed from a member having teeth similar in height and pitch to one of the rack gears. The teeth of this member are then cut by a tool at the desired intersection angle as if the teeth of a height and pitch of the other rack gear were being made. For the present case wherein the rack gears intersect at about 90° and the height and pitch of the teeth on each rack are generally identical, the resultant machined part resembles the pyramid gear 66 shown in FIG. 2. Gear 66 is characterized by the square based

pyramid shaped teeth 71. The pyramids 71 have a height and peak-to-peak separation (in the directions of the two racks) that permit the pinion gears 33 and 34 to run over it on rack 8 and pinion gears 40 and 41 to run over it on rack 11.

The rack gears are seated in the grooves 80-83 cut into the frame 2. The grooves are laid out in a tic-tac-toe pattern with horizontal grooves 80 and 81 intersecting the vertical grooves 82 and 83 (as seen in the plan view of FIG. 4). The rectangular cross-section of the grooves (FIG. 3) is designed to mate with the cross-sectional shape of the rack gears. The pyramid gears are positioned at the intersections of the grooves meaning that each rack gear is separated into three pieces. For clarity of presentation the rack gears are discussed as continuous members because the pyramid gears in fact enable them to function as if they are continuous.

Other modifications to the above described invention will be apparent to those skilled in the art and are intended to be incorporated herein.

What is claimed is:

1. Photoelectrophoretic imaging apparatus comprising at least first and second roller electrodes supported for travel over a plate electrode with at least one roller traveling in a direction to intersect over the plate the path followed by at least one other roller, means for coupling voltage sources to said plate and said rollers to establish electric fields between said rollers and said plate, and exposure means for exposing photoelectrophoretic ink between a roller and plate to activating electromagnetic radiation to create images from ink exposed to radiation and subjected to field.

2. The apparatus of claim 1 further including a blocking web wrapped around said first roller and wound between feed and take-up reels, said web being wound onto the take-up reel at a velocity about equal and opposite to the velocity of the roller as it travels over said plate.

3. The apparatus of claim 2 further including a transfer web wrapped around said second roller, wound on a supply reel and pulled therefrom by drive rollers, said drive rollers capable of pulling the transfer web around the second roller at a velocity about equal and opposite to the velocity of the second roller as it travels across the plate.

4. The apparatus of claim 1 including first, second and third roller electrodes with the first and second roller electrodes following the same path over the plate having voltages coupled to them for formation of an image and for a second exposure of the formed image and with the third roller traveling across the plate along a path intersecting the path of the first and second rollers and having a voltage source coupled to it for transferring an image from the plate toward the third roller.

5. The apparatus of claim 4 wherein the path of the third roller intersects the path of the first and second rollers at an angle of about 90°.

6. The apparatus of claim 1 including at least first, second and third roller electrodes with said first and second rollers supported to travel the same path and the third roller supported to travel a path intersecting the path of the first and second rollers

wherein said first roller has a voltage coupled to it for electrophoretically depositing particles in a photoelectrophoretic ink over said plate,
wherein said second roller has a voltage coupled to it for forming an image from electrophoretically deposited ink and
wherein said third roller has a voltage coupled to it for transferring an ink image from the plate toward the third roller.

7. The apparatus of claim 1 including at least first, 10 second and third roller electrodes with said first and second rollers supported to travel the same path and the third roller supported to travel a path intersecting the path of the first and second rollers

wherein said first roller has a voltage source coupled to it for forming an image from photoelectrophoretic ink,
15

wherein said third roller has a voltage coupled to it for a second exposure of the formed ink to said radiation and
20

wherein said second roller has a voltage coupled to it for transferring a twice exposed ink image from the plate toward the second roller.

8. The apparatus of claim 6 wherein blocking webs (3) are wrapped around said first and second rollers 25 between feed and take-up reels for each web with motor means coupled to said take-up reels to pull the blocking webs from their feed reels past said rollers at a velocity about equal and opposite to the velocity of the rollers as they travel over said plate.

9. The apparatus of claim 8 further including a transfer web wrapped around said third roller and coupled to means for pulling the transfer web around the third roller at a velocity about equal and opposite to the velocity of the third roller as it travels over the plate.

10. Photoelectrophoretic imaging apparatus comprising

a first electrode and at least one roller electrode supported for movement relative to each other, feed and take-up reels positioned on the same side of said roller and opposite to the side of the roller adjacent said first electrode and fixedly supported relative to the roller electrode, a web wound between said reels and wrapped around said roller between the roller and first electrode, means for coupling voltages between said electrodes to establish an electric field, and means for exposing a photoelectrophoretic ink between said electrodes to activating electromagnetic radiation to form an image.

11. The apparatus of claim 10 wherein said roller electrode and said reels fixedly supported relative thereto are supported for travel over an area on said first electrode.

12. A photoelectrophoretic process comprising exposing photoelectrophoretic ink on a transparent plate electrode to activating electromagnetic radiation,

moving a first roller electrode and said plate relative to one another along a first path,

moving a second roller electrode and said plate relative to one another along a second path intersecting the first path,

coupling voltage potentials to said first and second electrode to establish an electric field across said ink whereby images are formed from ink exposed to light and subjected to field.

30 13. The process of claim 12 wherein said second path intersects the first path at an angle of about 90°.

14. The process of claim 12 wherein said rollers move over a stationary plate electrode.

35 15. The process of claim 12 wherein said plate moves over stationary first and second rollers.
